United States Patent Office

Des. 198,445
Patented June 16, 1964

198,445

BEACH CABANA

Gordon E. Williams, Pittsburgh, Pa., assignor to Contempra/Craft Corporation, Sewickley, Pa., a corporation of Pennsylvania

Filed July 18, 1963, Ser. No. 75,859

Term of patent 3½ years

(Cl. D13—1)

FIG. 1

FIG. 2

FIG. 3

FIGURE 3 is a side perspective view thereof with the top rotated downwardly to form a complete enclosure; and,

I claim:

The ornamental design for a beach cabana, as shown.
